UNITED STATES PATENT OFFICE.

NANNIE K. HUNT, OF ADOLPHUS, KENTUCKY.

SOLE AND HEEL FRAME.

1,410,064.

Specification of Letters Patent. Patented Mar. 21, 1922.

Application filed March 5, 1921. Serial No. 449,873.

To all whom it may concern:

Be it known that I, NANNIE K. HUNT, a citizen of the United States, residing at Adolphus, in the county of Allen and State 5 of Kentucky, have invented certain new and useful Improvements in Sole and Heel Frames, of which the following is a specification, reference being had therein to the accompanying drawings.

10 This invention relates to sole and heel frames for shoes and it has for its object to provide a metallic frame permanently united with the body portion of a shoe and adapted to detachably receive soles and heels so that 15 one sole or heel may be readily substituted for the other and thus render it possible for the user to wear leather or rubber heels or soles at will.

The device further renders it possible for 20 the user to quickly substitute a new sole or heel for a worn sole or heel with a very slight effort, in a very short time and without the use of skilled labor.

In the accompanying drawing:

25 Fig. 1 is a side elevation of a shoe showing the invention applied thereto;

Fig. 2 is a bottom view of the shoe;

Fig. 3 is a transverse vertical sectional view through the sole portion of the shoe 30 upon line 3—3 of Fig. 2;

Fig. 4 is a vertical sectional view upon line 4—4 of Fig. 2; and

Fig. 5 is a detail sectional view through the heel.

35 Like numerals designate corresponding parts throughout the several figures of the drawing.

Referring to the drawing 5 designates a shoe having a thin sole element 6 and a thin 40 heel element 6^a permanently united with and constituting a part of the body of the shoe. The frame for the reception of the sole consists of a metallic strip 7 which overlaps the thin sole 6 sufficiently to permit of the frame

45 7 being secured to said sole 6 by nails or like fastening devices, 8. A removable sole section 9 which may be of either rubber or leather has its edges undercut in such manner as to be engaged by an inwardly directed portion 10 of the frame 7. Metallic strips 11 and 12 are hinged to the rear ends of the frame 7 at 13 and 14 and when these strips 50 are swung transversely across the shoe and in rear of the otherwise open end of the

55 frame 7, the sole section 9 is secured against removal from the frame 7. Any suitable

means may be employed for uniting the ends of the strips 11 and 12. I prefer to employ a flexible strap section 15, one end of which is secured to the strip 11 and the other end of which is adapted to detachably engage the strip 12 in any suitable way, such, for example, as by an ordinary snap fastener 16 of a usual and well known construction. Such as is ordinarily employed upon gloves.

60 The structure at the heel of the shoe is substantially the same as that which holds the sole. That is it comprises a metallic strip 17 having a portion 18 which overlaps the side of the part 6^a of the body of the shoe and is secured thereto by nails or like fastening devices as indicated at 19. The strip 17, however, does not extend as near to the bottom of the heel 20 as the strip 7 extends to the bottom of the sole 9. Upon the contrary the strip 17 engages the removable heel section 20 adjacent its upper edge and to this end the removable heel section 20 is provided with a groove 21 extending therearound which receives an inturned flange 22 70 formed upon the lower edge of the plate 17 (see Fig. 5).

75 The inner end of the heel frame 17 is closed by strips 23 and 24 which are hingedly connected to the frame 17 at 25 and 26 and the ends of which strips are adapted to be united by a flexible strap section 27, one end of which is attached to one of the strips and the other end of which is united with the other of the strips by a snap fastening indicated at 28.

80 Thus if it be desired to substitute one section 20 for another, the snap fastening 28 may be released, the strips 23 and 24 swung outwardly and the new heel section 20 85 slipped into the open end of the frame 17 after which the strips 23 and 24 may be swung back to their former position and secured, thereby holding the heel section firmly in place within the frame 17.

100 The same procedure is followed in placing a new sole section 9 in the frame 7.

It is to be understood that the invention is not limited to the precise construction set forth but that it includes within its purview 105 whatever changes fairly come within either the terms or the spirit of the appended claim.

Having described my invention, what I claim is:

110 The combination with a shoe comprising a permanently united sole and heel part, of in-

dependent metallic frames, one extending around the toe of the shoe and one around the heel of the shoe, both of said frames comprising rounded end portions and substantially straight side portions comprising inwardly directed flanges, transversely extending rigid closure strips hingedly connected to the inner ends of the sides of each of said frames, means for exerting a drawing action upon and uniting the free ends of said strips and removable heel and sole sec-

tions which are slipped into said metallic frames and retained by the flanges and closure strips thereof, said heel and sole sections each having vertical inner end walls 15 against which said closure strip abut, said strips preventing inward movement of the said heel and sole sections.

In testimony whereof I hereunto affix my signature.

NANNIE K. HUNT.
